TABLE COVER.

No. 20,986.

Patented Aug. 11, 1891

UNITED STATES PATENT OFFICE.

JULIUS PEGEL, OF PHILADELPHIA, PENNSYLVANIA, ASSIGNOR TO JOHN BROMLEY & SONS.

DESIGN FOR A TABLE-COVER.

SPECIFICATION forming part of Design No. 20,986, dated August 11, 1891.

Application filed January 30, 1891. Serial No. 378,715. Term of patent 3½ years.

To all whom it may concern:

Be it known that I, JULIUS PEGEL, a subject of the Emperor of Germany, residing at Philadelphia, in the county of Philadelphia and State of Pennsylvania, have invented a certain new and original Design for a Table-Cover or Curtain, of which the following is a specification, reference being had therein to the accompanying drawing.

10 My invention relates to the surface ornamentation of a table-cover or curtain; and it consists of the design illustrated in the accompanying photographic drawing.

Its leading feature is the proportionately-wide floral border A, surrounding an oval field center.

I claim—

The design for a table-cover or curtain, substantially as shown and described.

In testimony whereof I affix my signature in presence of two witnesses.

JULIUS PEGEL.

Witnesses:

EDWARD BROMLEY,
ADOLPH PETZOLD.
